UNITED STATES PATENT OFFICE.

IRA JAMES, OF MATTOON, ILLINOIS.

APPARATUS FOR GENERATING GAS.

SPECIFICATION forming part of Letters Patent No. 311,493, dated February 3, 1885.

Application filed December 10, 1883. (No model.)

To all whom it may concern:

Be it known that I, IRA JAMES, a citizen of the United States, and a resident of the city of Mattoon, county of Coles, State of Illinois, have 5 invented certain new and useful Improvements in Apparatus for Generating Gas and Means for Conveying the Same, for use in connection with gas-engines; and I do declare the following to be a full, clear, and exact description of 10 the invention, which will enable others skilled in the art to which it appertains to make and use the same, reference being had to the accompanying drawing, and to the letters of reference marked thereon, which form a part 15 of this specification.

My invention has relation to gas-engines for motive power and the means and apparatus for furnishing and generating gas for such purpose. The objects are, first, to provide simple 20 and adequate mechanism in connection with air and volatile oil to generate a combustible gas to be used as a motive power in connection with gas-engines; second, to provide such means as are necessary to increase the combustible 25 power of the gas generated; third, to provide in connection with any gas-engine the means of generating the gas for its own consumption and enabling gas-engines to be used where no 30 regular gas-works exist; fourth, to provide a portable apparatus for generating gas as a motive power for gas-engines, which may be readily moved from place to place. I attain 35 these objects by the use of the following mechanism.

Similar letters refer to similar or corresponding parts.

The figure is a view in elevation of my apparatus complete.

A is a gas and oil reservoir, having a side 40 gage, N, with cocks n, and inlet-pipe and cock L, and conveying or conducting gas-pipe K, with stop-valve S, also an induction-pipe, I, entering the bottom, and gas-outlet pipe M at the top.

B is an air-reservoir, having the induction-pipe I of the reservoir A, connecting with the pipe F, forming a goose-neck.

On the top of the air-reservoir B is a vertical vent-pipe, G, terminating in a pop-valve, H.

Connecting with the air-reservoir B by the pipe E, having suitable valve therein, is an air-pump, C, having connected with the pis-

ton or plunger-rod U at its top a lever-handle, V, also on its side a band-wheel, T, with suitable crank, and at or near its base an inlet-air-pipe, D, with valve. 55

Connecting with the top of the reservoir or holder A is the pipe M, which is continued until it supplies three gas-jets of the Bunsen pattern beneath the air receiver or reservoir B. 60

O is a draw-off pipe and cock. J is a body of oil.

The manner of operating my invention is as follows: I shut the valves S and O and P, and then open the valve in the inlet-pipe L and 65 pour such quantity of volatile hydrocarbon oil in the vessel A as may be necessary, care being taken not to carry it above the upper draw-cock in the gage N. I then close the valve in pipe L, and commence pumping, by 70 the use of the lever-handle V, air into the air-reservoir B until the pop-valve H on the pipe G indicates I have the desired pressure. I then disconnect the lever-handle V and connect the pump C to line or engine-shaft by means of 75 band and band-wheel T. I then open the valve S of the connecting or conveying pipe K, which permits the gas generated to pass on to the engine for use. Motion being given to the engine it transmits to the band-wheel T 80 of the pump C, thereby keeping up the flow or pressure of air into the receiver B, and from thence into the vessel A. If in its practical 85 operation I find that my gas is not strong enough to afford sufficient combustion, I then open the valve P in the pipe M, and conduct gas down to three Bunsen burners, m, underneath the air-reservoir B, and ignite as many as necessary, and heat the air in its passage 90 through the reservoir B, which in a heated state flows into the body of volatile oil in the gas and oil reservoir, causing the oil therein to volatilize with greater rapidity. I carry the induction-pipe I in the form indicated to prevent the oil from flowing back into the air-reservoir B. 95

In addition to the above, if deemed necessary, I can tap the pipe K and lead therefrom another pipe to gas jets or burners for illuminating purposes, for use in connection with the 100 apparatus.

Having thus fully described my invention, what I claim, and desire to secure by Letters Patent of the United States, is—

1. The combination of the carburetor and gas-reservoir A, the elongated cylindrical air-reservoir, the air-pump, the goose-neck pipe I, connecting the base of the carburetor with the air-reservoir, a pipe connecting the pump with the air-reservoir, the burners located below the air-reservoir, and a gas-supply pipe, all arranged and operating as described.
2. The combination of the air-pump, the connected elongated cylindrical air-reservoir having as essential parts an indicator and pop-valve, the carburetor and gas-reservoir A, the bent or goose-neck pipe connecting the carburetor with the air-reservoir, and a gas-conducting pipe leading from the carburetor, and provided with burners located beneath the air-reservoir, as described, and for the purpose set forth.

15
In testimony that I claim the above as my own I affix my signature in the presence of 20 two witnesses.

IRA JAMES.

In presence of—
HARRY JAMES,
JAMES BEATTY.
